THREAD-GUIDING ARRANGEMENT

René Bouvet, Drexel Hill, and William L. Spann,
Boothwyn, Pa., assignors to American Viscose
Corporation, Wilmington, Del., a corporation of
Delaware

Application December 9, 1941, Serial No. 422,223

8 Claims. (Cl. 242—131)

This invention relates to apparatus for facilitating unwinding continuous filamentary material, such as strands or yarns, in sequence from a plurality of packages thereof.

It is an object of the invention to provide a novel arrangement of apparatus for guiding continuous filamentary material sequentially from a plurality of packages without interruption to a common point from which the continuous filamentary material may be drawn to a common winding device, such as a warping beam or cone winder or to a machine utilizing the material, such as knitting or sewing machines. While the device is hereinafter described with particular reference to textile filamentary material, yet it is applicable as well to filamentary material in general including ropes, cables and wires not necessarily adapted to textile use. The scope of the expression "filamentary material" is intended to include such materials of non-textile as well as textile utility.

The single figure of the drawing illustrates the invention in perspective.

As is shown in the drawing, the device comprises means for supporting a pair of cakes or other packages (such as bobbins, cones, balls, etc.) of yarn or filamentary material. This means for supporting the packages may consist of any stationary base, such as an ordinary table or bench. The drawing shows two such tables, 2 and 3, though a single supporting table or bench may be employed instead. The yarn packages or cakes 4 and 5 rest upon the supports 2 and 3 respectively. A pair of guides 6 and 7 are supported, as by means of the fixed upright 8 and the cross bar 9 secured thereto, above the cakes 4 and 5 and roughly in alignment with their centers. A guide 10 is symmetrically disposed above the guides 6 and 7 and is hereinafter referred to as the control or master guide. Spring clips 11 and 12 are suitably supported outside the region of ballooning of the yarn as it proceeds from the package being unwound through its corresponding guide thereabove. As shown in the drawing, these clips are supported by bars 13 and 14 extending longitudinally outwardly from the cross bar 9. However, these bars 13 and 14 may extend at any angle from cross-bar 9 provided the yarn extending from the clip to a point beneath the nearest guide in cross bar 9, such as yarn length 15, does not interfere with the ballooning portion of the yarn, such as yarn length 16, as it proceeds upwardly through the same guide in the cross bar. If desired, the supports for the clips may be fastened to other stationary bases, such as the tables 2 and 3 respectively. The upper peripheries of the guides 6 and 7 may be provided with notches 17 and 18 respectively, at points opposite or away from the peripheral portions of the periphery of such guides across which the yarn length 16 is drawn as it is un-

wound from the package and conducted to guide 10.

In operation of the device, the end of the yarn on the outside of the package 5 is threaded 5 through guide 7 and master guide 10 to whatever winding or other take-up device may be desired. The trailing end of the yarn upon the inside of the cake 5 is fastened, such as by tying, splicing, cementing or soldering, at 19, to the leading end of the yarn on the outside of package 4, which, previously to being tied or otherwise fastened, is led upward through guide 6 and downward through guide 7, and thence into the clip 12 to form a loop 20 beneath guide 7. The threading of this leading end of package 4 through the notch 18 of guide 7 assures that it will not interfere with the yarn being unwound from package 5 as it proceeds through guide 7. The trailing end of the yarn on the inside of package 4 is withdrawn and caught within the clip 11, thus holding this end in readiness for subsequent tying to the leading end of the next package to be put upon support 3 in place of package 5 after package 5 has been completely 15 unwound. When package 5 is completely unwound, its trailing end pulls the leading end of package 4 from clip 12 thus taking the loop 20 entirely through guide 7 and then directly withdrawing the yarn from package 4 through guide 20 6 and through master guide 10. A fresh package 25 may be supplied to table 3, the leading end of which will be threaded up through guide 7 around the top of guide 6, through notch 17 and down through guide 6 to be tied to the inside yarn 30 end of package 4 held in clip 11 to form a closed loop similar to loop 20.

While the outside end of the package is described as the leading end, that is, the first to be unwound, and the inside end is the trailing end, 35 the arrangement may be reversed, if desired, it being only necessary in such event to lead off the inside end first and tie the inside end of the other package to the outside end of the one being unwound and looping in a manner analogous to 40 that described above. It is not essential that the axis of the packages be parallel. The arrangement is not limited to the use of a pair of packages. Three, four or any number of packages may be employed, a guide and clip being 45 provided for each package and the respective trailing and leading ends of the several packages being tied to unwind the packages in any desired order. Furthermore, a plurality of unwinding arrangements, whether involving a pair 50 or a larger number of packages, may be employed, such as in a warping creel.

While a preferred embodiment of the invention has been disclosed, the description is intended to be illustrative only, and it is to be understood that changes and variations may be 55 made without departing from the spirit or scope 60

of the invention as defined by the appended claims.

What we claim is:

1. A device for facilitating unwinding of packages of filamentary material in sequence comprising a plurality of closed guides for filamentary material, means for supporting a plurality of wound packages of filamentary material, each in unwinding relation with respect to a corresponding one of said plurality of guides, and means for releasably holding a loop formed by uniting the trailing end of one of said packages with the leading end of another of said packages extending from the latter package directly through its corresponding guide and back through the guide corresponding to the former package out of the region of ballooning of the former package.

2. A device for facilitating unwinding of packages of filamentary material in sequence comprising a plurality of stationary closed guides for filamentary material, means for supporting a plurality of wound packages of filamentary material, each in unwinding relation with respect to a corresponding one of said plurality of guides, means for releasably holding a loop formed by uniting the trailing end of one of said packages with the leading end of another of said packages extending from the latter package directly through its corresponding guide and back through the guide corresponding to the former package out of the region of ballooning of the former package.

3. A device for facilitating unwinding of packages of filamentary material in sequence comprising a plurality of stationary closed guides for filamentary material, means for supporting a plurality of wound packages of filamentary material each in unwinding relation with respect to a corresponding one of said plurality of guides, a master guide for directing the filamentary material in succession from each of said plurality of guides through a common point, and means for releasably holding a loop formed by uniting the trailing end of one of said packages with the leading end of another of said packages extending from the latter package directly through its corresponding guide and back through the guide corresponding to the former package out of the region of ballooning of the former package.

4. A device for facilitating unwinding of packages of filamentary material in sequence comprising a plurality of stationary closed guides for filamentary material, means for supporting a plurality of wound packages of filamentary material each in approximate alignment with a corresponding one of said plurality of guides, a master guide approximately symmetrically disposed with respect to said plurality of guides for directing the filamentary material in succession from each of said plurality of guides through a common point, and means for releasably holding a loop formed by uniting the trailing end of one of said packages with the leading end of another said packages extending from the latter package directly through its corresponding guide and back through the guide corresponding to the former package out of the region of ballooning of the former package.

5. A device for facilitating unwinding of packages of filamentary material in sequence comprising a plurality of stationary guides for filamentary material, means for supporting a plurality of wound packages of filamentary material.

each in approximate alignment with the corresponding one of said plurality of guides, a master guide approximately symmetrically disposed with respect to said plurality of guides for directing the filamentary material in succession from each of said plurality of guides through a common point, a notch in the face of each of said plurality of guides nearest said master guide but away from the portion of the face nearest said master guide, and means for releasably holding a loop formed by uniting the trailing end of one of said packages with the leading end of another of said packages out of the region of ballooning of the former package.

15 6. A device for facilitating unwinding of packages of filamentary material in sequence comprising a plurality of stationary closed guides for filamentary material, means for supporting a plurality of wound packages of filamentary
20 material each in approximate alignment with a corresponding one of said plurality of guides, a master guide approximately symmetrically disposed with respect to said plurality of guides for directing the filamentary material in succession
25 from each of said plurality of guides through a common point, and a spring clip for releasably holding a loop formed by uniting the trailing end of one of said packages with the leading end of another of said packages extending from the latter package directly through its corresponding guide and back through the guide corresponding to the former package out of the region of ballooning of the former package.

7. A device for facilitating unwinding of packages of filamentary material in sequence comprising a plurality of stationary closed guides for filamentary material, means for supporting a plurality of wound packages of filamentary material each in approximate alignment with a corresponding one of said plurality of guides, a master guide approximately symmetrically disposed with respect to said plurality of guides for directing the filamentary material in succession from each of said plurality of guides through a common point, and means associated with each of said plurality of guides for releasably holding a loop formed by uniting the trailing end of a corresponding one of said packages with the leading end of another of said packages extending from the latter package directly through its corresponding guide and back through the guide corresponding to the former package out of the region of ballooning of the former package.

55 8. A device for facilitating unwinding of packages of filamentary material in sequence comprising a plurality of stationary closed guides for filamentary material, means for supporting a plurality of wound packages of filamentary
60 material each in approximate alignment with a corresponding one of said plurality of guides, a master guide approximately symmetrically disposed with respect to said plurality of guides for directing the filamentary material in succession
65 from each of said plurality of guides through a common point, means for releasably holding a loop formed by uniting the trailing end of one of said packages with the leading end of another of said packages extending from the latter package
70 directly through its corresponding guide and back through the guide corresponding to the former package out of the region of ballooning of the former package.
